W. E. SCHWARZMANN.
HIGH TENSION DISTRIBUTER FOR MAGNETOS.
APPLICATION FILED NOV. 9, 1918.

Patented Mar. 23, 1920.

UNITED STATES PATENT OFFICE.

WOLFGANG ERNEST SCHWARZMANN, OF SPRINGFIELD, MASSACHUSETTS, ASSIGNOR, BY MESNE ASSIGNMENTS, TO AMERICAN BOSCH MAGNETO CORPORATION, OF NEW YORK, N. Y., A CORPORATION OF NEW YORK.

HIGH-TENSION DISTRIBUTER FOR MAGNETOS.

1,334,803.

Specification of Letters Patent. Patented Mar. 23, 1920.

Application filed November 9, 1918. Serial No. 261,763.

To all whom it may concern:

Be it known that I, WOLFGANG E. SCHWARZMANN, a citizen of the United States, residing at Long Meadow, Springfield, in the county of Hampden, State of Massachusetts, have invented certain new and useful Improvements in High-Tension Distributors for Magnetos; and I do hereby declare the following to be a full, clear, and 10 exact description of the invention, such as will enable others skilled in the art to which it appertains to make and use the same.

The present invention relates to high tension distributors for magnetos, and particularly for magnetos for igniting the combustible mixtures in internal combustion engines having many cylinders, as eight or more.

Heretofore it was customary to connect the spark-plug distributing contacts to terminals, such as binding posts or outlets, around the face of the distributor block where one circular series of contacts was used, or along the top of or entirely around the distributor block where one, two or more circular series of contacts were used. Now when the engine associated with the magneto has many cylinders, as eight or more, the terminals to which the spark plug cables 20 are connected, may be too close together when arranged on the face of the distributor block, unless the block is of unduly large diameter and therefore of excessive weight; and the conductors embedded in the block and connecting the distributor contacts with the terminals may be too long and too crowded when the terminals are spaced along the top of the block, unless the block is of unduly large size and therefore of excessive weight. Furthermore, the leakage distance between the terminals at the face of the block or at the top thereof is insufficient in many cases to provide securely against misfire under severe and 30 exposed conditions of operation. So also, where the terminals are arranged entirely around the distributor block, the connections to the terminals underneath the block may be inaccessible, and too close to the mechanical interrupter below or even necessitate a change from this usual relative arrangement of the distributor and interrupter.

In order to overcome these difficulties, it

has been proposed to divide a single circular series of contacts, and the series of terminals connected thereto, into two or more circular series. While this arrangement increases the peripheral separation of adjacent contacts and adjacent terminals, the axial length of the distributor and the number of 55 rotatable brushes thereof are increased, thereby increasing the weight of the distributor parts especially when applying the arrangement to a two spark magneto for generating sparks simultaneously at the two 60 spark plugs of each cylinder of the engine. 65

The primary object of my invention is to provide a distributor having one or more circular series of contacts for regular or irregular intervals of ignition of a single or two 70 spark magneto, wherein the embedded conductors are not unduly long or crowded, and the terminals are not too crowded although of a comparatively large number, the size and weight of the distributor block being 75 kept down at the same time. I accomplish this object, by providing a distributor block of generally triangular outline with stepped terminals arranged along the outer periphery of the two sides 80 of the triangle meeting at the top, the bottom of the block preferably being devoid of terminals so that all the cables may be connected and disconnected conveniently and so that the distributor block may be arranged at its usual place directly above the 85 mechanical interrupter without being of undue axial length. Some of the stepped terminals, and particularly those near the bottom of the block, are angularly offset 90 from the others, and increasingly so toward the bottom, in such manner that, in the preferred embodiment disclosed hereinafter, the terminals effectively utilize the outer periphery of a block of distinctively appropriate shape for the purpose. In this 95 way, the outer periphery of the distributor block approaches an outline concentric with the inner periphery along which are located the series of distributor contacts, thereby 100 reducing the size and weight of the distributor block and shortening the embedded conductors, besides separating those conductors from each other and providing an increased leakage distance between the 105 terminals at the outer periphery of the

block, even where there is a comparatively large number of terminals in each series.

By associating two or more races in a distributor block of this kind with two or 5 more rotating brushes, a twin or multiple distributor is provided for single or two spark magnetos, the races being sufficiently separated by intervening insulating material to give the necessary leakage or creeping 10 distance between the adjacent contacts and the terminals therefor.

In the accompanying drawings illustrating these preferred embodiments of my invention in application, as an example, to a 15 magneto of the sleeve type intended to be associated with a 4-cycle 12-cylinder engine, Figure 1 is a longitudinal section of certain parts of a two spark magneto having a twin distributor for irregular firing; Fig. 2 is an 20 elevation of the distributor end of the magneto; Fig. 3 is a section, partly broken away, on line 3—3 of Fig. 1; Fig. 4 is a wiring diagram; and Fig. 5 is a vertical section of a 25 similar distributor for a single spark magneto.

The magneto has magnets 1, a rotatable sleeve 2 supported in bearings 3 and carrying the magneto gear 4 and the distributor pinion 5, and an armature 6 fixed in bearings 7 by the locking disk 8 and having a generating winding comprising the primary turns 9 and the secondary turns 10. A mechanical interrupter of any suitable kind 30 is arranged in the housing 11 having the 35 cap 12.

In the embodiment shown in Fig. 1, the twin distributor has two distributor brushes 13 and 14 fast with the distributor gear 15 and connected by the inside conductor 16 40 and the outside conductor 17 through the two collector brushes (not shown) to the two insulated terminals of the secondary turns 10 in the well known way. The twin distributor block 18 of insulating material 45 has two races around the inner periphery, one with the circular series of spark-plug distributing contacts 19 arranged around its inner periphery to be successively engaged by the brush 13 and the other with the 50 circular series of spark-plug distributing contacts 20 arranged around its inner periphery to be successively engaged by the brush 14. The two races, together with the intervening spacing and positioning ring 21, 55 are secured to the magneto structure directly above the mechanical interrupter by means of the triangular spider 22 having the screws 23.

The distributor block is of generally triangular outline, having a plurality of stepped terminals or seats 24 arranged along the two sides of the triangle meeting at the top. The seats near the top are horizontal, but those near the bottom are angularly off-set therefrom, and increasingly so toward 60

the bottom, so that the outer periphery of the block approaches an outline concentric with its inner periphery along which the spark plug contacts are arranged. Each of these stepped seats has a terminal at the end 70 of a conductor 25 leading to one of the distributing contacts, and is connected to a cable 26 leading to the insulated electrode of one of the spark plugs 27 of the engine.

As shown in Fig. 4, the two terminals of 75 the secondary turns 10 are connected to the two distributor brushes 13 and 14, whereas the insulated terminal of the primary turns 9 is connected to the insulated circuit contact 28 of the mechanical interrupter, the 80 other terminal of the primary turns and the other circuit contact 29 being grounded. One series of the spark-plug distributing contacts is connected to one set of the spark plugs of the engine, and the other series of contacts 85 is connected to the other set of spark plugs, the arrangement being such that, at each period of ignition, sparks are produced simultaneously at the two spark plugs of a cylinder. The magneto selected for illustration 90 is intended to be associated with a 4-cycle engine requiring irregular firing, as, for instance, a 12-cylinder engine having its cylinders arranged on a 45° V. Since this engine requires ignition at 45°, 75°, 45°, 75°, and so 95 on throughout the rotation of the crank shaft, the spark plug distributing contacts of each series are arranged according to that recurring irregular spacing, whereas the cam member 30 of the mechanical interrupter has 100 its cams spaced at 67.5°, 112.5°, 67.5°, and 112.5°, corresponding to the four positions of maximum generation of the magneto in each rotation, the sleeve 2 being driven by the gear 4 at one and a half times crank 105 shaft speed and the distributor brushes being driven by the gears 5, 15 at one-third that speed, equal to cam shaft speed.

In the second embodiment shown in Fig. 5, there is but one series of spark plug distributing contacts 31 and one series of terminals, the distributor being intended for association with a single spark magneto for regular or irregular firing, as desired. The single distributor brush 32 is fast with the 110 distributor gear 33. The distributor block 34 has a series of stepped terminals arranged, as in the first embodiment, along the two sides of the generally triangular periphery of the block and connected to the spark plug 115 cables 35.

In both of the foregoing embodiments, it will be apparent that the terminals or seats near the bottom of the block are angularly offset from the horizontal ones near the top 120 of the block, and that the angular extent of the offset increases toward the bottom, so that not only is the leakage distance between adjacent terminals increased, but as a result 125 of the fact that the periphery of the block 130

approaches an outline concentric with the inner periphery, the conductors 25 between the contacts along the inner periphery and the terminals at the outer periphery are 5 comparatively short and well separated. Furthermore, the average radial depth of the distributor block does not greatly exceed that of a ring in which the inner and outer peripheries are exactly concentric, even 10 though the distance along the surface, due to the stepped arrangement and also the generally triangular outline, greatly exceeds the periphery of such a ring.

It will also be observed that the base of 15 the block is devoid of terminals, so that all of the terminals are accessible for conveniently connecting or disconnecting the cable conductors. Furthermore, this construction permits the distributor block to be 20 arranged directly above the mechanical interrupter as heretofore.

Having thus described my invention what I claim is:—

1. In a high tension distributor for magnetos; a rotatable distributor brush; and a distributor block of generally triangular outline having a plurality of spark plug contacts circularly disposed around the inner periphery of the block and being successively engaged by the brush, and also having a plurality of stepped terminals connected to the contacts and arranged along the outer periphery of the two sides of the triangle meeting at the top, some of the terminals being angularly offset.

2. In a high tension distributor for magnetos; a rotatable distributor brush; and a distributor block of generally triangular outline having a plurality of spark plug contacts circularly disposed around the inner periphery of the block and being successively engaged by the brush, and also having a plurality of stepped terminals connected to the contacts and arranged along the outer periphery of the two sides of the triangle meeting at the top but not along the bottom thereof, some of the terminals being angularly offset.

3. In a high tension distributor for magnetos; a rotatable distributor brush; and a distributor block of generally triangular outline having a plurality of spark plug contacts circularly disposed around the inner periphery of the block and being successively engaged by the brush, and also having a plurality of stepped terminals connected to the contacts and arranged along the outer periphery of the two sides of the triangle meeting at the top, those terminals near the bottom being angularly off-set.

4. In a high tension distributor for magnetos; a rotatable distributor brush; and a distributor block of generally triangular outline having a plurality of spark plug contacts circularly disposed around the in-

ner periphery of the block and being successively engaged by the brush, and also having a plurality of stepped terminals connected to the contacts and arranged along the outer periphery of the two sides of the triangle meeting at the top, the terminals being increasingly offset angularly toward the bottom.

5. In a high tension distributor for magnetos; a rotatable distributor brush; and a distributor block of generally triangular outline having a plurality of spark plug contacts circularly disposed around the inner periphery of the block and successively engaged by the brush, and also having a plurality of stepped terminals connected to the contacts and arranged along the outer periphery of the two sides of the triangle meeting at the top, the terminals near the top being parallel to each other and those near the bottom being angularly offset therefrom.

6. In a high tension distributor for magnetos; a rotatable distributor brush; and a distributor block of generally triangular outline having a plurality of spark plug contacts circularly disposed around the inner periphery of the block and successively engaged by the brush, and also having a plurality of stepped terminals connected to the contacts and arranged along the outer periphery of the two sides of the triangle meeting at the top but not along the bottom thereof, the terminals near the top being parallel to each other and those near the bottom being angularly offset therefrom.

7. In a magneto; a mechanical interrupter; and a high tension distributor comprising a rotatable distributor brush, and a distributor block having a base located directly above the interrupter; said distributor block having a series of spark plug contacts circularly disposed around the inner periphery of the block and being successively engaged by the brush, and also having a plurality of stepped terminals increasingly offset angularly toward the bottom so as to approach an outline concentric with the inner periphery.

8. In a magneto; a mechanical interrupter; and a high tension distributor comprising a rotatable distributor brush, and a distributor block having a base located directly above the interrupter; said distributor block having a series of spark plug contacts circularly disposed around the inner periphery of the block and being successively engaged by the brush, and also having a plurality of stepped terminals increasingly offset angularly toward the bottom so as to approach an outline concentric with the inner periphery, the base of the block being devoid of terminals.

9. In a magneto; a mechanical interrupter; and a high tension distributor com-

prising a rotatable distributor brush, and a distributor block of generally triangular form having a base located directly above the interrupter; said distributor block having a series of spark plug contacts circularly disposed around the inner periphery of the block and being successively engaged by the

brush, and also having a plurality of stepped terminals arranged along the sides of the triangle, some of the stepped terminals being angularly offset and the base of the block being devoid of terminals. 10

In testimony whereof I affix my signature.
WOLFGANG ERNEST SCHWARZMANN.
